UNITED STATES PATENT OFFICE.

LAWRENCE B. JENCKES, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

LOOM-DRIVING MECHANISM.

Application filed July 12, 1921. Serial No. 484,228.

To all whom it may concern:

Be it known that I, LAWRENCE B. JENCKES, a citizen of the United States, residing at Worcester, in the county of Worcester and 5 State of Massachusetts, have invented a new and useful Loom-Driving Mechanism, of which the following is a specification.

This invention relates to a driving mechanism for looms which are used for weaving 10 very wide heavy fabrics in which looms the parts are subjected to unusually heavy strains. It is the general practice in loom building to apply power at one end only of the loom. Much difficulty has been encountered 15 however in these wide heavy looms because of the spring and yield of the parts which transmit the power across the loom. This has caused serious trouble in the operation 20 of the picking mechanism at the remote side of the loom, as it is necessary that the pick should be substantially identical and accurately timed on both sides of the loom.

It is the general object of my invention to provide for more uniform operation of the 25 mechanism by supplying power from two independent units to the two ends of the loom and it is a further object of my invention to provide novel devices for equalizing the application of power by these independent 30 units.

With these general objects in view, my invention relates more particularly to certain arrangements and combinations of parts which will be hereinafter described 35 and more particularly pointed out in the appended claims.

A preferred form of my invention is shown in the drawings in which

Fig. 1 is a partial front elevation of a 40 loom embodying my improvements;

Fig. 2 is a right hand side elevation of the parts shown in Fig. 1;

Fig. 3 is a partial sectional elevation taken along the line 3—3 in Fig. 1; and

Fig. 4 is a diagrammatic view of the connections from one of the shipper handles to the two ends of the loom.

Referring to the drawings, I have shown 50 portions of a loom frame 10 supporting bearings for a crank shaft 11 by which the lay is moved through the usual crank arms 12. Sleeves 13 are rotatably supported on the crank shaft 11 and picking rolls 14 are mounted to rotate with the sleeves 13 and

are also slidable axially thereon into and 55 out of position to engage the cam plates 15 on the pick shaft 16. The pick shafts are connected by arms 17 and links 18 to the picker sticks 19.

All of these parts are of the usual construction and form no part of my invention, 60 which relates particularly to the means for applying power to the crank shaft 11 and to the sleeves 13 which drive the picking rolls 14.

I will now describe the driving mechanism at the right hand side of the loom. A motor 20 is mounted on a base 21 and is provided with a pinion 22 which meshes with a large gear 23 which is loosely mounted to 70 slide on a shaft 24 rotatable in bearings in the loom frame 10 and in an outer frame 25 which is rigidly connected to the frame 10 by braces 26. A friction disc 27 is fixed to the shaft 24 and suitable controlling 75 mechanism to be described is provided for forcing the gear 23 against the disc 27, thus rotating the shaft 24.

A counter shaft 28 extends entirely across the loom and is supported in bearings in the main frame 10 and in the outside frames 25 and 25^a. The shaft 28 is driven from the shaft 24 by a pinion 29 on the shaft 24 which meshes with a gear 30 on the counter 80 shaft.

The counter shaft 28 is connected at each side of the loom to the crank shaft 11 by pairs of eccentric gears 31 and 32 and is also separately connected to each of the sleeves 13 by a pair of elliptical gears 33 and 34. A second motor 35 is provided at the left hand side of the loom and is similarly connected through a pinion 36 to a gear 37 loose on a shaft 38 to which a friction disc 39 is secured. The shaft 38 is connected by gears 40 and 41 to the shaft 28 previously described.

I will now describe the devices by which the gears 23 and 37 are moved against the friction plates 27 and 39, transmitting power 100 to the opposite ends of the shaft 28. Shipper handles 45 and 46 are preferably provided at each side of the loom, the two handles being connected by a rod 47 so that they may be used interchangeably. The handle 46 is pivoted at 48 on the frame 10 and has a pin and slot connection with a lever 49 pivoted to the frame at 50. The lower end 105

2
of the lever 49 is connected by a link 51 to one arm of a bell crank 52 which is pivoted at 53 and supports an equalizing lever 54.

One arm of the lever 54 is connected by a link 55 and bell crank 56 and link 57 to a lever 58 pivoted at one end on a bracket 59 and having a roll 60 positioned in a circumferential groove in the hub of the gear 23. The other arm of the equalizing lever 54 is similarly connected to a lever 61 which controls the position of the gear 37. Springs 62 normally draw the gears away from the friction plates as clearly indicated in Fig. 4.

In starting up a loom provided with my improved driving mechanism, the motors 20 and 35 are first started, thus revolving the sliding gears 23 and 37. One of the shipper levers 45 or 46 is then moved to apply tension to the levers 58 and 61 which move the gears into frictional contact with the discs 27 and 39. The equalizing lever 54 permits the two driving motors to pick up the load without placing an undue share of the load on either motor.

It will be noted that the two sides of the loom are connected through the shafts 11 and 28, so that it is impossible for the parts to vary from their timed relation. At the same time the greater portion of the power at each side is supplied at a point closely adjacent to the corresponding picking mechanism and I avoid the difficulties encountered when the power is transmitted through the shafts from one side of the loom to the other for picking purposes.

Having thus described my invention it will be evident that changes and modifications can be made therein by those skilled in the art within the spirit and scope of my invention as set forth in the claims and I

do not wish to be otherwise limited to the details herein disclosed but what I claim is:—

1. In a loom, connected driving mechanism operating at both sides of the loom, 45 separate power-applying devices at each side of the loom, and friction connections between said devices and said mechanism at each side of the loom.

2. In a loom, connected driving mechanism 50 operating at both sides of the loom, separate power-applying devices at each side of the loom, friction connections between said devices and said mechanism at each side of the loom, a manual controller 55 for said connections, and an equalizer between said controller and said connections.

3. In a loom, connected driving mechanism 60 operating at both sides of the loom, separate power-applying devices at each 60 side of the loom, friction connections between said devices and said mechanism at each side of the loom, a manual controller for said connections, linkage between said controller and said connections, and an 65 equalizing lever in said linkage.

4. In a loom, connected driving mechanism 70 operating at both sides of the loom, a separate electric motor at each side of the loom, and driving connections between each 70 motor and said mechanism.

5. In a loom, connected driving mechanism 75 operating at both sides of the loom, a separate electric motor at each side of the loom, driving connections between each motor and said mechanism, and a single manual controller for said connections.

In testimony whereof I have hereunto affixed my signature.

LAWRENCE B. JENCKES.
